UNITED STATES PATENT OFFICE

156,973

VENDING MACHINE CABINET

Harold N. Kinne, Peoria, Ill., assignor to Corson
E. Bobenmyer, Peoria, Ill.

Application November 10, 1947, Serial No. 142,414

Term of patent 14 years

(Cl. D52—3)

To all whom it may concern:

Be it known that I, Harold N. Kinne, a citizen of the United States, residing at Peoria, in the county of Peoria and State of Illinois, have invented a new, original, and ornamental Design for a Vending Machine Cabinet, of which the following is a specification, reference being had to the accompanying drawing, forming part thereof.

I claim:

The ornamental design for a vending machine cabinet, as shown.

HAROLD N. KINNE.
